UNITED STATES PATENT OFFICE

JOHN F. FRITZ, OF EVERGREEN PARK, ILLINOIS

AIRPLANE PROPELLER

Application filed November 24, 1930. Serial No. 497,882.

My invention relates to airplane propellers, and more particularly to the construction of the blades thereof, and my main object is to provide a propeller whose blade is designed to more fully engage the air displaced by the propeller.

A further object of the invention is to construct the blade of the novel propeller on dual lines, whereby to provide an auxiliary blade 10 to follow up the action of the main blade.

A still further object of the invention is to lend the auxiliary blade of the novel propeller a curvature designed to pocket or retain the air dissipated by the main propeller 15 blade, and so save such air for the action of the next propeller blade.

A final but nevertheless important object of the invention is to design the novel propeller blade in a single and rugged piece, 20 whereby to provide maximum strength and rigidity.

With the above objects in view and any others that may suggest themselves from the specification and claims to follow, a better 25 understanding of the invention may be had by reference to the accompanying drawings, in which—

Fig. 1 is an elevation of the novel propeller blade;

Fig. 2 is an edge view thereof from the right hand side of Fig. 1;

Fig. 3 is a rear elevation of the propeller blade;

Fig. 4 is an edge view opposite from that 35 of Fig. 2, and Fig. 5 is a section on the line 5—5 of Fig. 1.

It is a well known scientific fact that the conventional propeller dissipates a great deal 40 of air during its action, so that it only has a fraction of the proper efficiency during progress. Consequently, the propeller must be raced or spun at a high rate of speed in order to create sufficient propulsive force to induce a take-off of the craft or to keep the 45 same in motion. Various attempts have been made to alter the design of the propellers for the recovery of the lost motion or power referred to, but few attempts have resulted in gain.

In carrying out the objects aforesaid, I

use the standard propeller as a basis, the blade thereof being indicated at 10 in the drawings. However, I enlarge the hub portion 11 of the propeller sufficiently to form an auxiliary blade 12 spaced in substantial 55 parallelism from the main blade and connected with its outer end to the same by an integral spacer or connection 13. The main blade is made with a shallow recess 14 in one of its edges, and has the conventional 60 pitch and curvature. On the other hand, the auxiliary blade 12 has a hollow curvature as indicated in Figure 5 and is somewhat fan-shaped as shown in Figure 3. One of its sides overlaps the recessed portion 14 of the 65 main blade spacedly.

In the action of the propeller, it is intended to rotate in the direction of the horizontal arrow in Figure 1. In doing this, the main blade displaces the body of air, while the auxiliary one pockets a body of air. Thus, considering that the speed of the propeller is ample even at the ordinary rate, it will be seen that the body of air displaced by one propeller blade will be caught and pocketed 70 by the auxiliary blade of the next oncoming blade, so that it may be used for purposes of displacement in the line of travel rather than dissipation in a lateral or wasteful course. The dual propeller is not only a propeller 80 with twice the number of blades, but a propeller with blades which carry their own and immediate retaining members.

It will be seen that a propeller of the above description in action will displace a much 85 greater amount of air along the course of travel without being run at excessive speeds. Thus, a take-off may be effected without racing the engines of the craft and straining the latter unduly in an effort to gain lifting force. 90 Obviously, my propeller is designed to save the engines from excessive vibration, wear and tear and waste of fuel, as well as to accomplish without extra parts or mechanisms a marked increase of efficiency for the propeller.

I claim:—

1. A propeller formed with a main blade, an auxiliary blade adjoining the latter, both blades being integral extensions from the 100

propeller hub, the auxiliary blade extending radially in a fan-like form and with a transverse curvature presenting its hollow inwardly, and an integral reduction extended transversely from the outer portion of the auxiliary blade to meet and join the main blade.

5 2. A propeller formed with a main blade, and an auxiliary blade adjoining the latter, said adjoining blade having a transverse curvature with the hollow facing the main blade, and the latter being recessed in its rear edge within the expanse of the corresponding portions of the adjoining blade.

10 3. A propeller formed with a main blade, and an auxiliary blade adjoining the latter, said adjoining blade having a transverse curvature with the hollow facing the main blade, the latter being recessed in its rear edge within the expanse of the corresponding portions of the adjoining blade, and said recess being of arcuate profile.

In testimony whereof I affix my signature.
JOHN F. FRITZ.
